UNITED STATES PATENT OFFICE.

FREDERICK E. LUEBKERT, OF BROOKLYN, NEW YORK.

POWER-TRANSMISSION MECHANISM.

1,258,796.

Specification of Letters Patent. Patented Mar. 12, 1918.

Application filed September 26, 1913. Serial No. 791,914.

To all whom it may concern:

Be it known that I, FREDERICK E. LUEBKERT, a citizen of the United States, and a resident of Brooklyn, New York, in the county of Kings and State of New York, have invented certain new and useful Improvements in Power-Transmission Mechanism, of which the following is a specification.

- 10 This invention relates to power transmission mechanism of the type used in automobiles wherein it is desired to obtain a plurality of speeds while the motor is running at constant speed.
- 15 The invention is more particularly directed to improvements in the mechanism disclosed in my prior Patent No. 1,064,752, with the objects first, to provide the controlling mechanism with means for quickly disconnecting the transmission shaft from the motor shaft without throwing the intermediate mechanism into operation; second, to provide a more positively acting mechanism for adjusting the throw of the variable crank; 25 third, to gear the intermediate mechanism up so that a shorter stroke of the oscillating clutch member will suffice to give the required speed; fourth, to provide this gearing with means for securing reverse speed; and 30 fifth, to simplify the arrangement of parts, and to render them stronger and more compactly disposed.

The various further and subsidiary objects will more fully appear from the detailed description and the features of novelty will be particularly pointed out in the claims.

In the drawings illustrating this invention,

Figure 1 is a sectional plan view of my improved mechanism mounted within a casting which may be attached to suitable points of the frame of the vehicle.

Fig. 2 is a section taken along line 2—2 of Fig. 1, the parts being illustrated on an enlarged scale.

Fig. 3 is a diagrammatic view illustrating the formation of the cams on the controller for obtaining the various movements of the parts of the mechanism.

Fig. 4 is a sectional elevation of the actuating mechanism for the controller, the section being taken along line 4—4 of Fig. 5.

Fig. 5 is a plan of the control handles and indicator dial.

As in my prior patent above referred to, the motor shaft drives intermittent clutching

or gripping mechanism, the throw of which may be regulated to drive the transmission shaft at gradually varying speeds from rest up to the full speed of the motor shaft, whereupon the latter is coupled directly to the transmission shaft and the drive for the intermittent clutches may be adjusted so that the latter are rendered inoperative. The construction and arrangement of parts is, however, such as to greatly increase the strength and compactness of the apparatus.

Referring in detail to the drawings, the motor shaft 10 has keyed thereto a sleeve 11 formed with a face plate or head 12 upon which is mounted an adjustable eccentric 13. This eccentric is connected by an eccentric rod 14 with a pivoted bracket 15, which, in turn, is connected by links 16 and 17 to the drums 18 and 19, so as to impart an oscillating movement thereto, and, through suitable single-acting clutches or pawls, impart rotation to a sleeve 20 mounted upon the motor shaft. Fixed to this sleeve is a gear 21 meshing with a pinion 22 mounted upon a counter-shaft 23, suitably journaled in the frame. A gear 24 splined to the counter-shaft meshes with a pinion 25 fixed upon a squared end enlargement 26 formed on the transmission shaft 27. The latter is mounted in alignment with the motor shaft and the enlargement 26 thereof is formed with an axial socket into which extends the reduced end portion of the motor shaft. It is thus seen that, as the motor shaft rotates, it imparts, through the eccentric 13 and the connections therefrom, an oscillating movement to the drums 18 and 19, and the latter, through the single-acting clutches, impart a continuous rotation to the sleeve 20 and the gear 21 thereon, and thence the speed is stepped up through the gearing above described to the motor shaft 27.

To adjust the eccentric to the desired throw, the following mechanism is provided: A controller shaft 30 which is actuated by the operator in any suitable manner has mounted thereon a cam 31 to be hereinafter more fully described. This cam has a slot 32 in which extends a roller 33 mounted on an arm 34. The latter has a fork 35 straddling a grooved collar 36 formed on a sleeve 37, splined to the motor shaft. Projections 38 extend inwardly from the prongs of the fork into the groove of the collar. When the controller is actuated by the operator, the arm 34 is swung about its pivot and thus through its projections

engaging the grooved collar, adjusts the sleeve 37 longitudinally of the motor shaft. When the sleeve is so adjusted, it transmits its movement to the eccentric 13 as follows: 5 Extending from the sleeve 37 at diametrically opposite sides thereof are brackets 39, to which are connected, preferably by pivotal connections, the racks 40 meshing with the pinions 41, mounted diametrically opposite each other upon radial axes in a suitable carrier 42. The racks 40 are guided by the walls of the carrier extending about the same and engage the pinions from opposite sides so as to impart to the latter rotation 10 in opposite directions, which rotation is imparted to the bevel pinions 43 fixed to the pinions 41 meshing with a bevel gear 44 formed on a sleeve 45 loose upon the sleeve 11 above described. The sleeve 45 at the 15 end adjacent to the face plate 12 is provided with a head 46 having formed therein a spiral slot 47 into which extends a pin 48 projecting from the eccentric 13 through a radial slot 49 formed in the face plate 12. 20 It will thus be seen that when the controller is actuated to slide the sleeve 37 longitudinally along the motor shaft, the pinions will be rotated to turn the bevel pinions 43 and head 46, and thus through the spiral cam 25 slot into which the pin extending from the eccentric projects, adjust the latter radially so as to vary its throw. It will be understood, of course, that the eccentric is formed with an extended slot 50 through which the 30 shaft passes so as to permit the eccentric to move radially relative to the shaft.

When the eccentric has been adjusted so as to impart to the transmission shaft a speed equal to that of the motor shaft, the 35 latter may be coupled directly to the transmission shaft as follows: Mounted upon the controller shaft 30 is a second cam 51 having a slot into which extends a roll 52 mounted upon a rod 53 connected to operate 40 an arm 54 having fixed thereto a toothed segment 55. The latter meshes with a rack bar 56 which slides in a suitable guide within the casing and is formed with an upstanding arm 57 engaging a grooved collar 45 58 formed on a sleeve 59 slideable upon the squared end 26 of shaft 27. Fixed to the sleeve 59 in any suitable manner is a toothed member 60 which may be slid into mesh with a toothed member 61 fixed to the motor 50 shaft. Thus, when the transmission shaft has been speeded up by the intermittent clutching mechanism to a speed equal to that of the motor shaft, further movement 55 of the controller shaft actuates the cam 51 into position to operate the segment and rack and thereby shift the sleeve 59 along the transmission shaft and thus throw the toothed member 60 into engagement with the toothed member 61. The transmission 60 shaft is thus directly coupled to the motor

shaft, but the gear 25 remains in mesh with the gear 24, as the sleeve 20 by reason of the single-acting clutches, may then overrun freely while the cams are actuated to adjust the eccentric to neutral position. 70

I will now describe my improved construction whereby the transmission shaft may be quickly unclutched from the motor shaft and entirely disconnected from the driving mechanism without passing through the intermediate speeds. The cams 31, and 75 51, are shown as mounted upon a common axis, the cam 31 actuating the arm 34 fulcrumed at α and the cam 51 actuating the link 53 guided by a forked extension thereof 80 γ straddling the shaft 30. The position of the cams as shown in the diagram corresponds to the position in which the eccentric is adjusted to no-throw and the coupling member on the transmission shaft is disengaged from 85 the mating coupling member on the motor shaft. The motor is then running free and the transmission shaft is inoperative. When the cams are rotated in the direction of the arrow, the cam 31 will actuate the arm 34 to 90 increase the throw of the eccentric. According to the present construction in which the increase of speed is obtained by the movement of the arm 34 to the right, the cam 31 has a gradually increasing throw 95 from points α to b , the latter point representing the point at which the maximum throw is reached. While portion $\alpha-b$ of the cam 31 is engaging the arm 34, the portion $a'-b'$ of the cam 51 is engaging the link 100 53, the angles subtended by these portions being equal. The portion a' and b' of the cam 51 is concentric with the axis of rotation of the cams, and, therefore, does not actuate the rod 53, thus maintaining the coupling members 60 and 61 out of engagement 105 with each other during the time when the transmission shaft is being speeded up through the intermittent clutch mechanism. Further rotation of the cams in the same 110 direction brings the concentric portion $b-c$ of the cam 31 into engagement with the arm 34 and the inclined portion $b'-c'$ of the cam 51 in engagement with the link 53, operating the latter to throw the coupling members 60 and 61 into engagement with each other while the transmission shaft is being 115 driven at its highest speed by the intermittent clutch mechanism, which speed is about equal to the speed of the motor shaft. While 120 the cams are moving still farther in the same direction during which time the concentric portion $c-d'$ of the cam 51 is holding the transmission shaft coupled to the motor shaft, the retreating portion $c-d$ of the cam 125 31 actuates the arm 34 back into position, where the eccentric is adjusted to neutral and thus the intermittent clutching mechanism is rendered idle while the transmission 130 shaft is directly coupled to the motor shaft

and is being driven at full speed. In case the transmission shaft is coupled to the motor shaft before the former has quite attained the speed of the latter, no harm will be done because the sleeve 20 may then simply overrun by reason of the fact that a higher speed is impressed upon it than the single-acting clutches can impart to it, as previously explained.

Now, in case it is desired to uncouple the transmission shaft quickly and bring the vehicle to a sudden stop, so form the cams that the control shaft upon which the cams are mounted, may be further actuated in the direction of the arrow. Thus the portion $d-a$ of cam 31 is concentric and corresponds to the position of no-throw of the eccentric, whereas, the portion $d'-a'$ of cam 51 slopes inward and thus actuates the link 53 so as to throw the coupling members 60 and 61 out of engagement. A comparatively small movement of the controller handle by the operator will, therefore, quickly uncouple the transmission shaft from the motor shaft without throwing into operation the intermediate speed changing mechanism, and thus the vehicle will be brought quickly to a stop.

For reverse drive, the gear 24, which, it will be remembered, is splined to the counter-shaft 23, may be slid along the shaft by an actuating arm 62 which engages a grooved collar 63 formed on an extension of the hub of the gear. When so actuated, this gear 24 is thrown out of mesh with the pinion 25 and into mesh with a gear 64 fixed to a suitable back shaft or sleeve 65. The latter has fixed thereto a pinion 66 meshing with the pinion 25. When the motion is transmitted through this back shaft, it will be readily seen that the transmission shaft will be driven in the reverse direction.

When the reverse is thrown in, the controller shaft can be actuated only for a portion of its travel, so as to speed up the vehicle to only a fraction or any suitable proportion of its full speed. This is accomplished as follows: Referring to Figs. 4 and 5, the controller shaft 30 is geared by the bevel gears 70 and 71 to the vertical shaft 72 extending upward through the stationary tubular post 73 fixed to the vehicle. To this vertical shaft 72 is attached the controller handle 74 which extends over a dial 75, forming the cover of a casing 76 fast to the post 73. Mounted within the stationary tubular post and surrounding the vertical shaft 72 is a tubular shaft 77 connected by an arm 78 fixed at the bottom thereof and a link 79 to an arm 80 fixed to the reverse shaft 62. The reverse handle 81 is attached to the top of the tubular shaft 77 and is disposed mainly within the casing 76, the extremity of the handle projecting from the casing through a segmental slot 82 formed

in a vertical wall thereof. The hub of the reverse handle is formed with a segment 83 having on the top face thereof a recess 84 into which seats a plunger 85 extending through the dial 75. A spring 86 abutting against a plate 87 fastened to the dial and through which the plunger projects, engages a collar 88 on the plunger, thus holding the latter against the segment 83. When the reverse handle is at inoperative position as illustrated in Figs. 4 and 5, the plunger 85 seats in the recess on the segment and permits the free movement of the controller handle 74. However, as soon as the reverse handle is actuated to throw in the reverse, the plunger 85 is forced out of its recess and is held upward by the face of the segment, thus preventing the movement of the controller handle beyond a point sufficient to give the suitable speed desired for reverse drive.

To prevent the movement of the controller handle in the wrong direction tending to throw in the direct coupling 60-61 between the driven or transmission shaft and the motor shaft while the latter is at rest or has not been speeded up to the required degree by the intermittent clutch mechanism, I provide the controller handle with a spring pressed plunger 90 located preferably at the bottom of the handle. This plunger has a beveled face 91 adapted to engage the beveled face 92 of a tooth 93 upstanding from the dial 75. The beveled faces of the plunger and tooth permit the handle to pass the latter in one direction but not in the other. The tooth also is so located that as soon as the coupling 60 and 61 is disconnected, the plunger 90 passes this tooth and snaps back behind it. Thus to throw in the coupling, it is necessary to again pass through the intermediate speeds, so as to speed up the driven shaft to the speed of the motor shaft. Also when the vehicle is at rest the controller can be moved only in the proper direction to speed up the vehicle gradually and cannot be actuated to throw in the direct coupling until the vehicle has so been speeded up.

It will thus be seen that I have provided a comparatively simple compact mechanism whereby any desired speed may be obtained from rest up to full speed of the vehicle. Very little effort is required to adjust the speed changing device and the variation in speed may be obtained by imperceptible degrees from rest up to the full speed of the vehicle. The use of the usual friction clutch which is required in connection with change speed gearing hitherto employed, is obviated in the present mechanism and at the same time the driven or transmission shaft may be quickly uncoupled from the motor shaft without passing through intermediate speeds. Upon reverse drive the speed may

also be increased gradually, but only up to a certain point, thus preventing the possibility of accident in case of inadvertent or accidental excessive movement of the controller upon reverse drive. The stroke of the intermittent gripping or clutching mechanism is decreased by reason of the gearing up of the sleeve with the driven shaft, and accordingly the size of the reciprocating or oscillating parts and also their stroke are reduced to a minimum, thus rendering them more compact and decreasing their inertia.

Having thus described my invention, I claim as new and desire to secure by Letters Patent:

1. In power transmission mechanism, a driving shaft, a driven shaft, variable gripping mechanism actuated by the driving shaft, means for transmitting the variable speed of said gripping mechanism to the driven shaft, means for coupling the driven shaft directly to the driving shaft, means for varying the movement of said gripping mechanism, a controller for adjusting the gripping mechanism and for shifting the coupling means, said controller having means whereby the coupling is connected when the gripping mechanism has attained a movement sufficient to drive the driven shaft at a speed approximately equal to that of the driving shaft, said controller having also means whereby the gripping mechanism is adjusted to inoperative position after the driven shaft is coupled directly to the driving shaft and means for disengaging the coupling without throwing the gripping mechanism into operation.

2. In power transmission mechanism, a driving shaft, a driven shaft, a sleeve loosely mounted upon one of these shafts, means for imparting a variable speed to the sleeve from rest up to a fraction of the full speed of the driving shaft, a counter-shaft, means for gearing up said sleeve through said counter-shaft so as to drive the driven shaft substantially at the full speed of the driving shaft, and means for directly coupling the driven and driving shafts when the former has attained substantially the full speed of the driving shaft.

3. In a power transmission mechanism, a driving shaft, a driven shaft, intermediate gripping mechanism, step-up gearing between said driving and said driven shafts for speeding up the latter from a position of rest up to substantially the full speed of the driving shaft, the step-up gearing including a counter-shaft and a gear slidably thereon, a back shaft geared to the driven shaft, and means for shifting the slidably gear into mesh with the gear on the back shaft to secure a low speed reverse through the gripping mechanism.

4. In change speed mechanism, a driv-

ing shaft, a driven shaft, and means for gradually speeding up the driven shaft from rest up to approximately the full speed of the driving shaft, means for directly coupling the shafts when the driven shaft has so been speeded up, means whereby the movement of the same controller uncouples the shafts without passing the driven shaft through the intermediate speeds, and means for preventing the direct coupling of the shafts without passing the driven shaft through the intermediate speeds.

5. In change speed mechanism, a driving shaft, a driven shaft, means for gradually speeding up the driven shaft from rest up to approximately the full speed of the driving shaft, and means for directly coupling the shafts after the driven shaft has so been speeded up, a controller handle for controlling the change speed and the direct coupling of the shafts, a spring pressed plunger upon the handle having a beveled face, and a projection formed upon a stationary part coöperating with the plunger to prevent reverse movement of the controller after the direct coupling has been disconnected.

6. In change speed mechanism, a driving shaft, a driven shaft, variable speed transmission mechanism between the shafts for gradually speeding up the driven shaft from rest up to approximately the full speed of the driving shaft for forward drive, reverse drive mechanism, a controller for the variable speed transmission, a reverse handle, and means actuated by the reverse handle for preventing the movement of the controller further than necessary to secure a low speed upon reverse drive.

7. In change speed mechanism, a driving shaft, a driven shaft, variable speed transmission mechanism between the shafts for gradually speeding up the driven shaft from rest up to approximately the full speed of the driving shaft, reverse drive mechanism, a controller for the variable speed transmission, means for directly coupling the shafts when the driven shaft has been so speeded up, a reverse handle, and means operated thereby for preventing movement of the controller to couple the shafts.

8. In change speed mechanism, a driving shaft, a driven shaft, variable speed transmission mechanism between the shafts for gradually speeding up the driven shaft and for coupling the same directly to the driving shaft, reverse drive mechanism, a controller for the variable speed transmission, a reverse handle, a segment formed thereon and a spring pressed plunger operated by said segment to form a stop for the controller handle, and allowing only a portion of the full movement of the same when the reverse handle has been actuated to throw in the reverse drive.

9. In change speed mechanism, a driving shaft, a driven shaft, variable speed transmission mechanism between the shafts for gradually speeding up the driven shaft, reverse drive mechanism, a controller for the variable speed transmission, comprising a vertical actuating shaft, a stationary tubular post surrounding the same and formed with an enlarged casing, a dial on said casing, a controller handle mounted on the vertical shaft over said dial, means for shifting the reverse drive mechanism comprising a tubular shaft passing through the post and surrounding the vertical controller shaft, a handle attached to the tubular shaft and passing through a slot in the casing, a segment on the handle formed with a recess, and a spring pressed plunger passing through the dial and engaging the segment, said plunger being adapted to seat in the recess when the reverse handle is at neutral position and to be projected out into the path of the controller handle when the reverse handle has been actuated for reverse drive. ²⁰
